TYPEWRITING MACHINE

Henry A. Avery and Joseph P. Barkdoll, Groton, N. Y., assignors to L. C. Smith & Corona Type-writers, Inc., Syracuse, N. Y., a corporation of New York

Application October 9, 1941, Serial No. 414,358

20 Claims.

(Cl. 197—8)

The invention relates to improvements in typewriting machines and, more particularly, to typewriting machines for typing the scores and lyrics of music compositions.

Important purposes of the invention are to provide a typewriting machine with minimum variation from machines most commonly employed for ordinary text typing but well adapted for rapid typing of music scores and lyrics; to provide an improved coordinated arrangement of the types, type case changing means, line spacing means and line finding means of the usual typewriter facilitating rapid typing of such scores with or without accompanying lyrics; and to provide an improved forward and backward line spacing means of great accuracy particularly adapted for correct typing of music scores.

Other purposes and advantages of the invention will appear from the following description in detail of the preferred embodiment of the invention illustrated by way of example in the accompanying drawings.

To these ends the invention consists in the features of construction, arrangements of parts, and combinations of devices and elements particularly pointed out in the appended claims and hereinafter described.

In the drawings:

Figure 1 is a fragmentary top plan view of an otherwise known typewriting machine modified in accordance with the present invention.

Figure 2 is a fragmentary side elevation of the improved machine, with certain parts omitted as hereinafter pointed out and other parts broken away for simplicity and clarity of illustration of the improvements.

Figure 3 is a detail section on the line 3—3 of Figure 9, showing more particularly features of the line spacing mechanism with the operating handle or lever in normal idle position.

Figures 4 and 5 are detail views showing certain parts at the end of two successive forward line spacing operations of minimum extent, as hereinafter more particularly explained.

Figure 6 is a detail sectional view on the line 6—6 of Figure 9, showing the forward line spacing regulator adjusted, however, for a wider spacing than that for which said regulator is set in Figure 3.

Figure 7 is a detail sectional view on the line 7—7 of Figure 3, showing particularly the line space ratchet wheel detent means.

Figure 8 is a detail sectional view on the line 8—8 of Figure 9.

Figure 9 is a detail sectional view approximately on the line 9—9 of Figure 3.

Figure 10 is a detail sectional view on the line 10—10 of Figure 9.

Figure 11 is a detail front elevation of the line finder or indicator and part of the platen with certain adjacent parts removed and some broken away for clarity of illustration of the line finder.

Figure 12 is a diagrammatic view hereinafter explained.

Figure 13 is a view showing the type bearing heads and part of the shanks of five typical type bars of the machine.

Figure 14 is a detail sectional view showing the known segment shift stops of the known machine in connection with which the improvements are illustrated.

The improvements have been illustrated as embodied in their preferred form in a known Smith-Corona portable typewriting machine having a type bar action and type bar segment shifting case shift mechanism such as shown in U. S. patent to H. A. Avery, No. 2,001,759, issued May 21, 1935, although it will be obvious that the improvements may be embodied in a wide variety of known machines. Only so much of the known machine as is necessary to a clear understanding of the improvements has been shown and will be described.

The machine has the usual arcuate system of type bars 20 pivoted in the usual type bar segment 21 and operable by the usual key actions (not shown). The segment is shiftable downwardly from a normal lower case printing position to upper case printing position by the usual shift key means. The usual stop member 22, shiftable bodily with the segment, is engageable with an upper case limit stop 23 on the stationary main framework of the machine and carries the usual lower case stop 24 normally engaged with lower case limit stop 25 on the main framework. The type action system and case shift means are more fully shown and described in the patent above referred to.

The usual roller platen 26 is journaled in the end plates 27 and 28 of the usual platen carriage, which carriage is supported on the usual ball bearings to travel horizontally transversely of the main frame on the usual carriage bed 29

which is fixedly held to the main frame. The usual finger wheels 30 are connected with the platen for rotating the latter. The usual type bar guide 31 is held to the type segment, as usual, in the machine shown. The types print through the usual inked ribbon 32 threaded

through the usual ribbon vibrator, parts of which are shown at 33 in Figure 1. It will be understood, of course, that the machine is provided with the usual escapement mechanism for feeding the platen carriage, and with the usual ribbon feeding and vibrating means for the inked ribbon 32. The usual letter space scale 34 and paper table 35 are mounted on the carriage. The improvements will now be described.

Each type bar head or type block 36 is provided with two types, one of which prints in one case position of the shiftable type segment and the other of which prints in the second case position of the segment. A few typical ones of the type bars are shown. The types which print in normal case position include a full set of alphabet, punctuation and numeral types while the types which print in the other case position are music types for printing the staff, notes and various music signs required to type a music score. The types of the two sets are designated respectively as 37 and 38 on the drawings.

The set of types 37 are set on the type blocks in known manner for lower case types to type with their bases along the usual writing line of the known machine, said line being indicated by the upper edge portions of the usual line indicating wings 39 of the line indicator 40. At least one of the wings 39 is preferably graduated as usual at 41 to indicate a plurality of letter space positions of the platen carriage. According to the present invention, the line indicator or finder (which is fixedly held to stationary parts on the main frame of the machine by the usual pair of screws 42) is provided with specially located additional line indicating means 43 and 44 correlated with the types of the machine as hereinafter explained.

The pointer portions 43 of the indicator indicate the writing line for the set of types 38, which line is coincident with that struck by the third or middle line of the staff-printing type of the machine, or the middle line of a staff typed by repeated operations of the staff-printing type. This writing line, as will be observed from the diagrammatic view (Figure 12) showing upper and lower case impressions made by the types of the five type bars shown in Figure 13, passes horizontally centrally through the note head impressions and such impressions as a clef sign, for example. The five horizontal line printing parts of the staff-printing type face shown on the type bar head at the left in Figure 13 are made long enough for slight lateral overlapping or merging of successive impressions made by this type. The size of the note heads, as usual, should not exceed the spacing between the staff lines.

Figure 12 shows successive upper and lower case impressions made by the five type bars shown in Figure 13, the staff lines being projected across the view by dash lines. It will be noted that the writing line of the lower case or "correspondence" characters is one and one-half staff line spaces or three degrees of the staff below the writing line of the music characters or the middle or third line of the staff. Consequently, it will be noted that the two sets of type characters are set on the bar heads so that the writing line spacing of the types on the bar heads for the two sets is greater by three degrees of the staff than the extent of case shift movement.

It will also be noted that the lower case or "correspondence" characters have a maximum height not exceeding two degrees of the staff, said height being preferably approximately equal

to the spacing of the staff lines. The lower case types preferably are a font of lower case or small capitals with punctuation types and numeral types of corresponding size. Lower case Elite Gothic types are shown. The machine may be operated in lower case in the usual manner to type lyrics or ordinary correspondence. The staff typed by the machine is a widely used size in printed music.

10 Special line spacing mechanism is provided for line spacing the platen forwardly and backwardly. This mechanism is coordinated with the types and staff size to facilitate writing of music scores and also use of the machine to type correspondence. It is also designed to insure accurate spacing within the necessary narrow limits, and retention of the platen in accurately spaced position. The spacing apart of the staff lines typed by the machine shown is .0812 inch approximately and is in any case relatively small for the most commonly used sizes of staffs in printed music. It is necessary also to be able to line space one degree of the staff or one-half of the short spacing between staff lines, as is well known.

25 In the line spacing mechanism shown, the line space ratchet wheel 45 (which is held to platen 26 in the known manner to rotate with the platen about the platen axis) has its teeth so spaced that a single tooth space movement of the wheel 45 will turn the platen 26 an extent equal to the space between two adjacent lines of the staff, i. e., two degrees of the staff. The ratchet wheel shown has 49 teeth, and in order to rotate the platen to line space the paper one degree of the staff it is necessary to be able to rotate the ratchet one-half of a tooth space and hold it so rotated for typing. The use of a relatively coarse toothed ratchet such as shown is highly advantageous in obtaining accurate spacing and in preventing accidental skipping of ratchet teeth as well as accidental overrunning. Inaccurate lines spacing is a known fault of mechanisms employing fine toothed ratchets.

40 45 A stationary bearing bushing 46 coaxial with the platen has its outer end fixed in carriage end plate 27 and extends inwardly through the ratchet wheel which turns about this bushing. An upstanding pawl-carrying arm 47 is journaled at its lower end on bushing 46 to rock fore and aft of the machine, the lower end of the arm or pawl carrier being confined between the ratchet wheel and a collar 46^a formed on the exterior of the bushing. A pivot stud 48, fixed to and extending through the upper end of the pawl carrier 47 longitudinally of and parallel to the platen axis, has journaled thereon at the right hand face of the pawl carrier the adjacent ends of the two line space pawls 49 and 50 of identical construction.

60 65 The pawl 49 is for forward line spacing and pawl 50 is for rearward or backward line spacing. The axis of stud 48 is above the ratchet wheel and in a plane radial to the wheel axis. Pawls 49 and 50 normally extend respectively rearwardly and downwardly and forwardly and downwardly toward the toothed periphery of the wheel which is thick enough to be overhung by, and engaged by, both pawls. Each pawl is formed at its free end and lower edge with a notched nose or twin noses 51. The twin noses 51 of each pawl are shaped to closely straddle and fit the top portion of a tooth of ratchet 45, or to enter simultaneously and closely fit a tooth space of the ratchet.

The free ends of the pawls 49 and 50 are constantly urged toward each other and toward the ratchet wheel by a single tension spring 52 connected to studs 53 fixed to the pawls. The pawl carrier 47, and the line space lever hereinafter described, are held in intermediate normal idle position by a pair of rigid upstanding and oppositely bowed return or centering arms 54 which are journaled at their lower ends on a fixed pivot screw 55 and are constantly urged toward each other by a connecting tension spring 56. The upper ends of arms 54 straddle or embrace stud 48 and normally engage and exert opposing pressures on the stud.

Pivot screw 55 is held to a stationary plate or bracket 57 which is tightly fitted on the collar 48* of bushing 46 and is also affixed to a stud 58 fixedly held to carriage end plate 27. Plate 57 has a cam hump 59 (Figure 6) normally engaged by studs 53 on the line space pawls 49 and 50 to hold both pawls disengaged from the ratchet 45.

Bracket 57 is formed forward of the free end of pawl 50 with a laterally extending stop lug 60 for pawl 50, and is formed rearward of pawl 49 with a laterally extending stop lug 61 for pawl 49. Lug 60 is inclined to the wheel periphery and so spaced from the normal position of pawl 50 as to arrest said pawl when it has rotated the ratchet one-half of a tooth space and to jam said pawl tightly to the ratchet after said rotation. Lug 61 is inclined to the wheel periphery and so spaced from the normal position of pawl 49 as to arrest said pawl when the pawl has rotated the ratchet one and one-half tooth spaces and thereupon jam said pawl tightly to the ratchet to prevent overthrow of the ratchet and pawl.

Pivoted to bracket 57 to the rear of lug 61 on a horizontal pivot 62 is a three-arm forward line-space changing or regulating lever 63 having a handle 64 and two limit stop lugs 65 and 66 engageable with bracket 57 to limit rocking of said lever. When lever 63 is rocked to the position shown in Figure 6, the lug 61 will be engaged by pawl 49 on forward line spacing and the mechanism is set for a forward spacing extent of one and one-half tooth spaces. When lever 63 is rocked to the position shown in Figures 3, 4 and 5, a third stop lug 67 bent laterally from said lever is interposed between pawl 49 and lug 61 to arrest and jam-lock pawl 49 when said pawl has rotated the ratchet one-half of one tooth space.

To actuate the pawls selectively for forward or backward line spacing as desired, a line space lever 68 is journaled on a headed bearing sleeve 69 (Figure 9) held to stud 58. Said lever 68 is formed with a rearwardly extending finger piece or handle 70 depressible for forward line spacing, and is formed with a forwardly extending finger piece or handle 71 depressible for backward line spacing. In Figures 4 and 5 are shown the end of two successive operating strokes of pawl 49 with regulator 63 set as in Figure 3. As shown in Figure 3, it will be observed that the notched noses of both pawls are identically related to the adjacent ratchet teeth so that if either finger piece is depressed, the notched nose of the effective pawl will enter a tooth space. Successive half-tooth space rotations of the wheel by either pawl will cause its notched nose to alternately fit into a tooth space and fit over the top of the next following tooth.

Above its pivotal axis, line space lever 68 is formed with an inward extension 68* which over-

hangs end plate 27 and is formed with an up-and-down extending slot 72 in its inner end. Stud 48 is engaged in this slot, so that when lever 68 is rocked it will rock the pawl carrier 47.

Ratchet detent means are provided for yieldingly detaining the ratchet wheel against rotation in either direction at any half-tooth space position. This means includes an arm 72 having at its rear end a yoke bearing on a horizontal pivot stud 73 fixed to and extending inward from carriage end plate 27. Extending inward below the ratchet wheel from the forward end of this arm 72 and fixed thereto is a pivot stud 74 on which is pivoted a small yoke or rocker 75, on which are journaled on horizontal axes above and respectively fore and aft of the axis of yoke 75 two small detent rollers 76 and 77. These rollers are so spaced apart that when either thereof is engaged in a tooth space of ratchet 45, the other is seated against the top or apex of a tooth of said ratchet. Arm 72 is constantly urged upward by a strong tension spring 78, stronger than spring 52 and connected to the arm 72 and a part of the paper table 35, to press the detent rolls 76 and 77 upward against the toothed periphery of ratchet 45.

Stud 58 also serves as a stop to limit rocking of the centering arms 54 under pull of spring 56, but there is a constant clearance between arms 54 and the bushing 46—46* which is straddled by the arms.

A suitable friction washer 80 is interposed between one face of the regulator lever 63 of the line space mechanism and the adjacent face of bracket 57 to hold lever 63 in each of its effective positions.

During operations of the line space mechanism the stud 53 on the idle one of the line space pawls 49—50 rides slightly along the arcuate top of cam hump 59 on bracket 57. The arcuate top of this hump 59 is concentric with the axes of the platen, ratchet wheel and pawl carrier.

With the parts positioned as in Figure 3, depression of finger piece 70 will result in rearward rocking of pawl carrier 47, stud 53 of pawl 49 will ride down the rear edge of hump 59, nose 61 of pawl 49 will in its entirety enter the adjacent tooth space of the wheel, and the pawl will thereafter rotate the ratchet wheel. A similar action of pawl 59 will occur if finger piece 71 is depressed with the parts in the position shown in Figure 3. If the ratchet were rotated one-half of a tooth space from the position shown in Figure 3, the nose of the active pawl, upon actuation of the line space lever, would engage over the top of the adjacent ratchet tooth to drive the ratchet wheel.

The two sides of each tooth of the ratchet wheel are of equal length and make equal angles with a line radial to the wheel axis.

The peculiar correlation of the setting of the upper and lower case types on the type bars with relation to the extent of case shift movement of the type bar segment, the resultant peculiar relation of the "writing" lines of the music types and the text printing types, and the setting of the staff-printing type with relation to the setting of the note printing types has several advantages which will be apparent to those skilled in music notation. The said correlation also avoids "shadow printing" in a machine with conventional rotary platen and single case shift, which would otherwise occur due to the great height of certain music types as compared with ordinary text printing types employed in conventional

typewriting machines. By "shadow printing" is meant at least partial impression by types of one case when the machine is set for printing in the other case.

The described height of the text printing characters relatively to the staff line spacing is highly advantageous, and the height and relative arrangement of the text printing types with respect to the staff lines on the staff-printing type facilitates writing of cues, proper placing of time numerals on the staff, etc. Time indicating numerals should be medially bisected horizontally by certain lines of the staff in the known manner.

The correlation of the several indications of the line finding device with the "writing lines" of the two series of types and with the staff printable by the staff-printing type is also highly advantageous. Such indications not only facilitate finding the writing lines of the two sets of types within the limits of the staff, but are also useful to find staff and degree lines above and below a staff typed by the machine, and in locating lines for typing cues and lyrics in conjunction with staff notation typed by the machine.

The line spacing means is peculiarly adapted for accurate spacing within extremely narrow limits required in music typing without over-thrown or back lash, and is correlated for efficient use with the staff typed by the machine. The half-tooth forward or backward line spacings each feed the paper one degree of the staff, and the optional one and one-half tooth forward spacing affords complete clearance between successive lines of text typing. Extremely accurate extent of rotation of the platen and accurate holding of the platen in accurately spaced position are highly essential to typing intelligible music scores, and due to the small linear extent of a staff degree such accurate line spacing and platen detention must be obtainable with extremely fine limits of line space actuation of the platen ratchet. The line space mechanism disclosed permits a minimum line space driving of the ratchet corresponding to one-half of a tooth-space turn of the ratchet. The ratchet can be turned in either direction by the pawl mechanism and also by the finger wheels of the platen and will be detained at half-tooth intervals by the detent means shown.

We claim:

1. In a case changing typewriting machine having a platen and a set of types coactive with the platen to type correspondence in one case printing setting of the machine, a set of music score typing types coactive with the platen to type in the other case printing setting of the machine, the types and platen being relatively shiftable for case changing, and the types of one set being coactive with the platen to type on a different writing line from that on which the other set is adapted to type.

2. In a case changing typewriting machine with single case shift having a platen and a set of alphabet, numeral and punctuation types coactive with the platen to print text in one case printing setting of the machine, said alphabet types being capital types, a set of music types including a staff-printing type coactive with the platen to type in the other case printing setting of the machine, the said music types being mounted relatively to the first-mentioned set of types to coact with the platen along a writing line different from that of said first-mentioned set of types by a spacing equal to three degrees

of the staff printable by the staff-printing type, and the height of the alphabet and numeral types not exceeding and approximately corresponding to two degrees of the staff printed by the staff-printing type.

3. In a typewriting machine as claimed in claim 2, means for rotating the platen for line spacing paper forwardly and backwardly at will in increments shifting the paper an extent equal to one degree of the staff printable by the staff-printing type and settable to rotate the platen to line space paper forwardly an extent equal to three degrees of said staff.

4. In a typewriting machine as claimed in claim 1, line indicating means associated with the platen to indicate the writing lines of the two sets of types.

5. In a typewriting machine as claimed in claim 2, line indicating means associated with the platen including means to indicate the writing line of the first set of types, means to indicate the line upon which the staff-printing type will impress the third or middle line of the staff, and means to indicate the line upon which the staff-printing type will impress the second line of the staff, the line of impression of the middle line of the staff-printing type being the "writing line" of the music types.

6. In a single shift case changing typewriting machine having a rotatable platen roll and type bars carrying a set of alphabet, numeral and punctuation types coactive with the platen roll to print text along a writing line in the normal lower case printing setting of the machine, the platen and type bars being relatively shiftable for case-change, the combination of music types, including a staff-printing type, carried by the type bars for coaction with the platen to type in the upper case printing setting of the machine along a writing line coincident with the line of impression of the middle or third line of the staff-printing type, the locations of said music types on the type bars with respect to the first set of types being such with respect to the extent of case shift that the writing line of the music types is three degrees of the staff above the writing line of the first-mentioned set of types, means for indicating the writing lines of the first-mentioned set of types and the music types, and line spacing means for rotating the platen selectively forwardly or backwardly at will in increments of one degree of the staff printable by the staff-printing type.

7. A typewriting machine as claimed in claim 6, wherein the alphabet and numeral types are characterized in that the maximum height thereof is approximately equal to two degrees of the staff printable by the staff-printing type, and the line spacing means is characterized in that means is provided for setting it for forward line spacing in increments equal to three degrees of the staff printable by the staff-printing type.

8. A single case shift typewriting machine having a rotary platen and type bars each carrying two types and the platen and type bars being relatively shiftable a fixed extent to permit printing impressions of different types on a bar, the types on the bars effective in one relatively shiftable position of the platen and bars being music types and the music type on one of said bars being a staff-printing type having a face for printing simultaneously a portion of each of the five lines of a music staff, the said music types being located on the bar so that the "writing line" of all of the music types is coincident

with the third line of the staff printable by the staff-printing type, line spacing means to rotate the platen to line space paper in increments of one degree of the staff printable by the staff-printing type, and means to indicate said "writing line."

9. A single case shift typewriting machine as claimed in claim 8, wherein type bars of the machine carry text printing types effective in the other relatively shifted position of the platen and type bars to print.

10. A typewriting machine for typing music, including a rotary platen, a staff-printing type coactive with the platen for printing simultaneously a portion of each of the five lines of a music staff, said portions being long enough to merge end to end upon successive impressions of said type, a line space ratchet wheel held to the platen to rotate therewith coaxially with the platen and having its teeth spaced to rotate the platen to line space paper per tooth space rotation of said wheel two degrees of the staff printable by said staff-printing type, line spacing means coactive with said wheel to turn it selectively forwardly or backwardly at each operation in half-tooth increments, and yieldable detent means coactive with said wheel to detain it at any half tooth rotated position.

11. A typewriting machine as claimed in claim 10, wherein said line spacing means includes a regulating means whereby the line spacing means may be set to rotate the platen in one direction at a single operation through a plurality of half tooth spaces.

12. A typewriting machine as claimed in claim 10, wherein the line spacing means coactive with said ratchet wheel includes a pawl carrier oppositely rockable about the axis of said wheel, yieldable means for normally centering said carrier in idle position, a pair of pawls pivoted to the carrier and constantly spring-urged toward the platen, one pawl engageable with the wheel to turn the latter in one direction and the other pawl engageable with the wheel to turn the wheel in the opposite direction upon rocking of the carrier in different directions from its normal idle position, means for normally holding both pawls disengaged from the wheel and for holding each pawl out of engagement with the wheel during working and return strokes of the other pawl, and means for limiting the working strokes of the pawls, each pawl having a notched nose shaped to closely fit in a tooth space of the ratchet wheel and to closely fit over a tooth of the wheel alternately upon successive half-tooth rotations of the wheel by the pawl.

13. A typewriting machine as claimed in claim 10, wherein the detent means for the ratchet wheel includes a rocker, a pivoted arm supporting said rocker to tilt about an axis extending transversely of the wheel, a pair of detents on said rocker spaced for seating of one into a tooth space of the wheel while the other is seated on the apex of a tooth of the wheel, and spring means urging said arm to press said detents to the toothed periphery of the ratchet wheel.

14. In a typewriting machine of the class described, a rotatable platen, a line space ratchet wheel connected with the platen to rotate the latter, a pair of line space pawls operative on said wheel selectively to rotate it in opposite directions, means for actuating either pawl to rotate the wheel, each pawl having a notched nose shaped to closely fit either into a tooth space of the wheel or over a wheel tooth, and yield-

able detent means coactive with the wheel to hold the wheel in any half-tooth space rotated position.

15. In a typewriting machine of the class described, a rotatable platen, a line space ratchet wheel connected with the platen to rotate the latter for line spacing a work sheet, a pair of line space pawls selectively operable upon said wheel to rotate the latter in different directions, means for actuating the pawls to render the selected one effective to drive the wheel, each pawl having a notched nose closely fittable either into a tooth space of the wheel or over the top of a wheel tooth, a pair of detents each seatable in a tooth space of the wheel while the other is seated on the apex of a tooth of the wheel, and means for yieldingly urging said detents constantly to the toothed periphery of the ratchet wheel.

20 16. In a typewriting machine, a rotary platen, a line space ratchet wheel coaxial with the platen and rotative therewith, a pawl carrier rockable about the axis of the wheel and platen, yieldable detent means to hold the wheel at any half tooth space rotated position of the wheel, a pawl pivoted on the pawl carrier and spring-urged to the wheel, said pawl having a notched nose shaped to closely fit in its entirety in a tooth space of the wheel and to alternatively snugly receive in its notch a tooth of said wheel, means to normally hold said pawl retracted from the wheel, means to normally return the pawl carrier to an idle position, means to rock the pawl carrier from idle position to actuate the pawl to drive the ratchet wheel, and means to limit rotation of the wheel by said pawl to one-half of a tooth space of the wheel.

25 17. In a typewriting machine, a rotary platen, a line space ratchet wheel coaxial with the platen and rotative therewith, a pawl carrier rockable about the axis of the wheel and platen, yieldable detent means to hold the wheel at any half tooth space rotated position of the wheel, a pawl pivoted on the pawl carrier and spring-urged to the wheel, said pawl having a notched nose shaped to closely fit in its entirety in a tooth space of the wheel and to alternatively snugly receive in its notch a tooth of said wheel, means to normally hold said pawl retracted from the wheel, means to normally return the pawl carrier to an idle position, means to rock the pawl carrier from idle position to actuate the pawl to drive the ratchet wheel, and means selectively settable to limit rotation of the wheel by the pawl to either one-half of a tooth space of the wheel or a multiple of said one-half of a tooth space.

30 18. In a typing machine of the class described, a rotary platen, a ratchet wheel coaxial with the platen and rotative in unison therewith, a pawl carrying arm oscillative about the platen axis, yieldable means to hold the pawl carrying arm in an intermediate idle position, forward and backward line spacing pawls pivoted to the pawl carrying arm on a common axis, a fixed cam engageable by the pawls to normally hold both pawls out of engagement with the ratchet wheel and engageable by each pawl to hold it out of engagement with the ratchet wheel during working and return strokes of the other pawl, a line space lever oppositely tiltable about a fixed fulcrum and engaged with the pawl carrying arm to rock the latter in opposite directions from idle position upon tilting of said lever in opposite

directions from a normal idle position in which it is held by said arm, each pawl having a notched nose shaped to closely fit alternatively entirely into a tooth space of the ratchet wheel or over a tooth of said wheel, detent means co-active with said wheel to hold the wheel yieldingly in any one-half tooth space rotated position thereof, and control means for limiting rotation of the wheel by either pawl to one-half of a tooth space.

19. In a typewriting machine as claimed in claim 18, control means for limiting rotation of the wheel by the pawls, including a regulating means settable to permit rotation of the wheel

by one pawl a multiple of a one-half tooth space of the wheel.

20. In a typewriting machine as claimed in claim 18, detent means for the ratchet wheel including a rocker tiltable about an axis extending transversely of the ratchet wheel, a pair of detent rollers journaled on the rocker to seat one in a tooth space of the wheel while the other is seated on the apex of a tooth of the wheel, and a support for said rocker spring urged to press said rollers to the periphery of the ratchet wheel.

HENRY A. AVERY.

JOSEPH P. BARKDOLL.
